CHARGE FORMING DEVICE

Fred E. Aseltine, Dayton, Ohio, assignor, by
mesne assignments, to General Motors Corpora-
tion, Detroit, Mich., a corporation of Dela-
ware

Application September 14, 1933, Serial No. 689,351

26 Claims. (Cl. 261—34)

This invention relates to charge forming devices for internal combustion engines and more particularly to that type of charge forming device which comprises a plurality of primary mixing chambers, one for each intake port of the engine and which cooperate respectively with a plurality of secondary mixing chambers located adjacent the said intake ports and receiving a primary mixture of fuel and air from conduits connected with the primary mixing chambers while receiving air when required through an air manifold having a single air inlet for supplying air to all of the secondary mixing chambers.

An example of a charge forming device of this character is disclosed in the patents to Fred E. Aseltine et al., 1,913,741, issued June 13, 1933, and 1,537,938 issued December 5, 1933. The present invention is illustrated herein as embodied in a charge forming device of the general character shown in these patents.

In the device disclosed in the above application and in earlier devices of similar character, various means have been provided to control the proportions of fuel and air in the mixture under various operating conditions for the purpose of supplying to the engine a mixture having the desired fuel and air ratio to properly operate the engine under any and all operating conditions. Among these proportioning devices are certain structures for regulating the mixture proportions by variably controlling the admission of air and it is one object of the present invention to provide means for restricting the admission of air to the carburetor to some extent during operation following opening of the throttle at low and intermediate speeds and means for reducing the effect of this restricting means at relatively high speeds for the purpose of forming a somewhat leaner mixture at such high speeds. This object is accomplished by the provision of an auxiliary air valve which is opened by engine suction and a dash pot to retard the opening movement of such air valve, the dash pot being fully effective until the throttle approaches its fully opened position when said throttle operates means to reduce the retarding effect of the dash pot so that upon further opening of the throttle the opening of the auxiliary air valve is retarded to a lesser degree and consequently the valve will open more freely to admit a greater quantity of air upon opening of the throttle as the latter approaches fully open position.

Further objects and advantages of the present invention will be apparent from the following description, reference being had to the accompanying drawing wherein a preferred embodiment of the present invention is clearly shown.

In the drawing:

Fig. 1 is a vertical, longitudinal section through a charge forming device in which the present invention is embodied.

Fig. 2 is a fragmentary, transverse, vertical section on the line 2—2 of Fig. 1 showing the pump delivery conduit diagrammatically in dotted lines.

Fig. 3 is a fragmentary side elevation showing the throttle actuating mechanism.

The charge forming device comprises a carburetor unit which is adapted to be connected to an air manifold which has a plurality of outlet branches adapted to be connected to the engine block and communicating with the several engine intake ports. For the sake of simplicity, the manifold is not illustrated herein and the drawing shows only the carburetor unit itself.

This carburetor unit comprises a main housing 20 having an attaching flange 22 adapted to be secured to the manifold by machine screws. An air inlet coupling 24 is secured in position to register with an opening in the upper wall 30 of the housing 20 in any suitable way. A casting 26, having certain dash pot chambers and fuel passages formed therein, is secured by screws to the lower wall of the housing 20 and a sheet metal fuel bowl 28 is held tight against an annular shoulder 30 formed on the housing 20 by a screw 32 which is screwed into the casting 26. Fuel is conducted from a main source of supply to the fuel bowl through a conduit (not shown) and the flow of fuel to the bowl is controlled by a float (not shown) which operates in the usual manner to maintain a substantially constant level of fuel in the bowl. Fuel flows from the bowl 28 to a plurality of primary fuel nozzles 34, one of which is located in each of the primary mixing chambers 36, the construction of which is briefly described hereinafter. The fuel conduit between the fuel bowl and the nozzle comprises a vertical fuel passage 38 communicating at its upper end with a horizontal fuel canal 40 which connects with each of the nozzles 34 through orifices 42. Fuel is admitted from the fuel bowl to the passage 38 at all speeds through a fixed metering orifice 44 and at high

25

35

40

45

50

55

speeds additional fuel is supplied through an orifice 46 controlled by a valve 48 in the manner set forth in the above mentioned Patent 1,937,938.

5 Fuel is lifted from the fuel bowl through the above described fuel passages and primary fuel nozzles to the mixing chambers by the suction therein. Closing movements of the throttle cause a reduction in mixing chamber suction which 10 might permit the fuel column to drop sufficiently to cause a temporary fuel starting of the engine unless means be provided to prevent it. For this purpose a check valve 50 is provided in an enlarged chamber 52 at the junction of channels 15 38 and 40 and on reduction of suction in the mixing chamber, seats on the bottom of the chamber 52 preventing downward flow of the fuel.

In addition to the primary fuel nozzles a secondary fuel nozzle 54 is provided in each of the primary mixing chambers and extends upwardly for a considerable distance above the top of the primary nozzle. At relatively high speeds the mixing chamber suction is enough to lift fuel from 20 the secondary fuel nozzles as well as from the primary nozzles but at idling or low speed operation under heavy load, the suction is sufficient to lift fuel only to some point between the top of the primary nozzles and the top of the secondary 25 nozzles so that fuel flows only from the primary nozzles under these conditions. Each primary nozzle is provided with a fuel metering orifice 56 and each secondary with a similar orifice 58. The primary mixing chambers are connected 30 with primary mixture passages 60 by the restricted orifices 62 and the mixture passages 60 are parallel and close together as indicated in Fig. 2 of the drawing. When the carburetor is attached to the manifold these passages 35 register with conduits which convey the primary mixture to the secondary mixing chamber, as fully explained in the above mentioned copending application. Air passages 64 supply air to the primary mixture passages immediately in 40 advance of the restriction 62 as described in the 45 above mentioned Patent No. 1,937,938.

A single throttle valve 66 which extends across all of the primary mixture passages controls the flow therethrough and is provided with grooves 50 68 which register with the mixture passage. This throttle is operated by means fully disclosed in the above mentioned Patent No. 1,937,938 and which forms no part of the present invention.

55 All the air entering the carburetor except a small quantity of primary air which is admitted through orifices 70, flows through the air horn 24 and the flow is controlled by a main air valve 12 normally held against a seat 74 by a spring 60 76 received between the valve and a flange 78 projecting from a sleeve 80 which is slidably mounted on a stationary guide sleeve 82 fixed in the housing 20 and serving as a guide for the stem 84 to which the air valve is secured 65 in any suitable manner. When it is desired to choke the carburetor to facilitate starting of the engine, the flange 78 is adapted to be lifted by a lever 86 pivoted on a stud 88 fixed in the housing 20 and manually operable by an arm 90 to which is connected some suitable operating connection which extends to a point convenient to the operator of the vehicle. When the choke is operated, the air valve is held closed and sufficient air to carry the starting fuel from the nozzle

70 to the engine is admitted through the orifices 70, previously referred to.

The valve 72 admits air to a main air chamber 92 from which air flows to the primary mixture passages through an opening 94 in the floor of the air chamber and to the several secondary mixing chambers through a secondary air passage 96 which connects with an inlet in the manifold. A manually operable throttle valve 98 and a suction operated valve 100 secured 10 to shafts 102 and 104 respectively, control the flow of air through the passage 96 and the operating connections for these shafts are fully disclosed in the above mentioned Patent No. 1,937,938. On opening of either throttle 66 or 15 98 the suction in the air chamber 92 is increased when the air valve is opened against the tension of its closing spring to admit additional air and increase the quantity of mixture supplied to the engine. The opening of the air valve must be 20 retarded to some extent, however, to prevent admission of sufficient air to lean the mixture too much. A dash pot is provided to accomplish this result and to prevent fluttering of the air valve. This dash pot forms no part of this invention 25 and is not shown herein but comprises a cylinder formed in the casting 26 and a piston which is secured to the lower end of the air valve stem by any suitable means and slides in the cylinder. Fuel is supplied to the cylinder by leakage 30 around the piston or by a valve controlled port, or in any other suitable way.

In order to enable a better understanding of the present invention which relates primarily to means for controlling the opening movement 35 of the suction operated valve 100, the manner of operation of the two throttles and this valve will be briefly set forth hereinafter. The throttle 66 and the throttle 98 are connected for operation together. The connection includes a lost motion device which permits a predetermined opening of the throttle 66 before any accompanying movement of the valve 98 takes place, the construction being generally such that the throttle 66 can be opened sufficiently to permit an engine speed corresponding to a vehicular speed of approximately twenty miles per hour on the level before the valve 98 begins to open, after which the two valves open simultaneously. No opening movement of the valve 100 can take 50 place until the valve 98 begins to open.

The lost motion device comprises an arm 103 which extends from the throttle valve 66 and is connected by a lost motion linkage 105 to an arm 107 extending from shaft 102. It is not necessary to describe the specific construction of this linkage more particularly as it is no part of this invention. It is shown in Fig. 3, however, and may be of the same construction as that shown in the later patent.

The purpose of the valve 100 is to temporarily retard the flow of air through the air passage 96 on opening movements of the valve 98 to prevent an increased supply of air reaching the secondary mixing chambers before the increased supply of heavier primary mixture reaches such chambers resulting from the increase in suction to the fuel jets and to increased pressure differential between the outlet and inlet ends of the primary mixture tubes so as to reduce the time 65 necessary for the primary mixture to reach said secondary mixing chambers because of the resulting increase in the velocity of flow through the tubes. The effect of this valve is augmented by means of a fuel pump which comprises a cyl- 70 75

inder 106 in which slides a piston 108 pivotally connected to a rod 110 which, at its upper end, is pivotally connected to an arm 112 secured to one end of the primary throttle. The delivery conduit 109 from the pump leads to a chamber 114 which communicates with passages 116, one of which leads to each of the primary mixture passages. The pump supplies some additional fuel on opening of the throttle and the combined effect of both the valve 100 and the fuel pump is such as to supply a mixture which is enriched to the proper degree during the acceleration period following any opening movement of the throttle.

At very high speeds it is unnecessary to supply a mixture which is enriched to the same degree as it is necessary to supply at lower speeds to secure the desired results and it is the purpose of the present invention to provide means to reduce the retardation of the opening movements of the valve 100 as the latter approaches its wide open position so that the enriching effect produced by this valve is reduced at such high speeds. This result is accomplished by means which will now be described.

In order to retard the opening movement of the valve 100, a cylinder 120 is provided in which there is slidably received a piston 122 to which is pivotally connected a rod 124 which is pivotally connected at its upper end to an arm 126 projecting from the shaft 104 on which the valve 100 is secured. A check valve 128 permits fuel to flow from the fuel bowl to the cylinder 120 through an orifice 130 upon upward movements of the piston 122. Obviously, as the valve 100 moves toward open position, the piston 122 is depressed and since the valve 128 is closed on downward movements of this piston, the downward movement thereof is resisted to a considerable extent because the fuel in the cylinder 120 can only escape by leakage around the piston.

In order to reduce the resistance to the downward movement of the piston 122, there is provided in the bottom of the cylinder 120 a metering plug 132, which communicates with a passage 134 formed between a plate 136 secured to the bottom of the casting 26 by machine screws 137 and another plate 138 which is secured to plate 136 in any suitable manner. Communicating with the passage 134 is a small orifice 140 which connects with a cylinder 142 formed in the casting 26 adjacent the cylinder 106 and having an outlet 144 which is normally closed by a valve 146 held in closed position by a spring 148 received within the cylinder 142 between the valve 146 and the plate 136. This valve has a rod 150 integral therewith and extending upwardly through an orifice in the casting 26 which guides the valve in its vertical movements. This valve is adapted to remain closed until the primary throttle approaches close to its full open position and is then opened by means of an arm 152, which projects from rod 110 which operates the pump piston, and which engages the top of the rod or stem 150.

Obviously as the primary throttle 66 is opened and approaches its full open position, the projecting arm 152 will assume the position shown in dotted lines in Fig. 1 and will engage the stem 150 to move the valve 146 downwardly and open the port 144 which permits the escape of fuel from the cylinder 120 and greatly reduces the retarding effect of the dash pot which controls the opening movement of the valve 100, permitting said valve to open much more freely and more rapidly after the valve 146 is opened than pre-

viously thereto. This will cause the valve 100 to restrict the admission of air to a much less degree upon opening movement of the throttle at very high speeds than it does when said throttle is opened at low and intermediate speeds and hence reduces the enriching effect of such valve on the mixture under such operating conditions. 5

While the embodiment of the present invention as herein disclosed, constitutes a preferred form, it is to be understood that other forms might 10 be adopted, all coming within the scope of the claims which follow.

What is claimed is as follows:

1. A charge forming device for internal combustion engines comprising a mixture passage, 15 means for supplying fuel and air thereto, a throttle controlling the flow of mixture through said passage, a secondary air valve for supplying additional air to said mixture passage, means for controlling the mixture ratio, said mixture controlling means comprising a dash pot for retarding the opening movements of the secondary air valve and means operable by the throttle for reducing the retarding effect of said dash pot 20 on opening movements of the throttle at relatively high engine speeds, by comparison with the effect of the dash pot at lower speeds. 25

2. A charge forming device for internal combustion engines comprising a mixture passage, means for supplying fuel and air thereto, a throttle controlling the flow of mixture through said passage, a secondary air valve for supplying additional air to said mixture passage, means for controlling the mixture ratio, said mixture controlling means comprising a dash pot for retarding 30 the opening movements of the secondary air valve and means operable by the throttle for reducing the retarding effect of said dash pot when the throttle reaches nearly full open position to a greater degree than when the throttle is in more 35 nearly closed position.

3. A charge forming device for internal combustion engines comprising a mixture passage, means for supplying fuel and air thereto, a throttle controlling the flow of mixture through said 45 passage, a secondary air valve for supplying additional air to said mixture passage, means for controlling the mixture ratio, said mixture controlling means comprising a dash pot for retarding the opening movement of the secondary air 50 valve, the effect of said dash pot being controlled by the position of the throttle at intermediate and high speeds.

4. A charge forming device for internal combustion engines comprising a mixture passage, 55 means for supplying fuel and air thereto, a throttle controlling the flow of mixture through said passage, a secondary air valve for supplying additional air to said mixture passage, means for controlling the mixture ratio, said mixture controlling means comprising a dash pot for retarding 60 the opening movement of the secondary air valve, a valve for controlling the retarding effect of the dash pot and means operable by the throttle for operating said valve. 65

5. A charge forming device for internal combustion engines comprising a mixture passage, means for supplying fuel and air thereto, a throttle controlling the flow of mixture through said 70 passage, a secondary air valve for supplying additional air to said mixture passage, means for controlling the mixture ratio, said mixture controlling means comprising a dash pot for retarding the opening movement of the secondary air 75

valve, a valve for controlling the retarding effect of the dash pot and means operable by the throttle for opening said valve as the throttle approaches open position.

5 6. A charge forming device for internal combustion engines comprising a mixture passage, means for supplying fuel and air thereto, a throttle controlling the flow of mixture through said passage, a secondary air valve for supplying additional air to said mixture passage, means for controlling the mixture ratio, said mixture controlling means comprising a dash pot for retarding the opening movement of the secondary air valve, a valve for reducing the retarding effect 10 of the dash pot when opened and means operable by the throttle for opening the valve as the throttle approaches open position.

7. A charge forming device for internal combustion engines comprising a mixture passage, 20 means for supplying fuel and air thereto, a throttle controlling the flow of mixture through said passage, a secondary air valve for supplying additional air to said mixture passage, means for controlling the mixture ratio, said mixture controlling means comprising a dash pot for retarding the opening movement of the secondary air valve, a pump adapted to supply additional fuel to the mixture passage to also enrich the mixture, means connected to the throttle for operating the pump, and means operated by the pump operating means for reducing the retarding effect of the dash pot under certain operating conditions.

8. A charge forming device for internal combustion engines comprising a mixture passage, 30 means for supplying fuel and air thereto, a throttle controlling the flow of mixture through said passage, a secondary air valve for supplying additional air to said mixture passage, means for controlling the mixture ratio, said mixture controlling means comprising a dash pot for retarding the opening movement of the secondary air valve, a pump adapted to supply additional fuel to the mixture passage to also enrich the mixture, means connected to the throttle for operating the pump, and means operated by the pump operating means as the throttle approaches open position for reducing the retarding effect of the dash pot.

9. A charge forming device for internal combustion engines comprising a mixture passage, 40 means for supplying fuel and air thereto, a throttle controlling the flow of mixture through said passage, a secondary air valve for supplying additional air to said mixture passage, means for controlling the mixture ratio, said mixture controlling means comprising a dash pot for retarding the opening movement of the secondary air valve, a pump adapted to supply additional fuel to the mixture passage to also enrich the mixture, means connected to the throttle for operating the pump, a valve operable to reduce the retarding effect of the dash pot and means operated by the pump operating means for operating said valve.

10. A charge forming device for internal combustion engines comprising a primary mixture passage adapted to deliver a primary mixture of fuel and air to a secondary mixing chamber, 50 means for supplying fuel and air to said primary mixture passage, a secondary air passage adapted to supply additional air to the secondary mixing chamber, a secondary air valve in said passage, a primary throttle for controlling the flow through the primary mixture passage, means

including said air valve for controlling the mixture ratio under various operating conditions, said ratio controlling means being operable to enrich the mixture on opening movements of the throttle at relatively low speeds and means operable by the throttle for reducing the enriching effect of said means when the throttle is opened at relatively high speeds. 5

11. A charge forming device for internal combustion engines comprising a primary mixture 10 passage adapted to deliver a primary mixture of fuel and air to a secondary mixing chamber, means for supplying fuel and air to said primary mixture passage, a secondary air passage adapted to supply additional air to the secondary mixing chamber, a secondary air valve in said passage, a primary throttle for controlling the flow through the primary mixture passage, means for controlling the mixture ratio under various operating conditions, said ratio controlling means comprising a dash pot for retarding the opening movement of the secondary air valve and means operable by the primary throttle for regulating the retarding effect of the dash pot. 15

12. A charge forming device for internal combustion engines comprising a primary mixture 20 passage adapted to deliver a primary mixture of fuel and air to a secondary mixing chamber, means for supplying fuel and air to said primary mixture passage, a secondary air passage adapted to supply additional air to the secondary mixing chamber, a secondary air valve in said passage, a primary throttle for controlling the flow through the primary mixture passage, means for controlling the mixture ratio under various operating conditions, said ratio controlling means comprising a dash pot for retarding the opening movement of the secondary air valve, a valve for controlling the retarding effect of the dash pot and means operable by the primary throttle for 25 operating said valve as the throttle approaches open position.

13. A charge forming device for internal combustion engines comprising a primary mixture 30 passage adapted to deliver a primary mixture of fuel and air to a secondary mixing chamber, means for supplying fuel and air to said primary mixture passage, a secondary air passage adapted to supply additional air to the secondary mixing chamber, a primary throttle for controlling the flow through the primary mixture passage, a secondary throttle in the secondary air passage, a secondary air valve in said secondary air passage, means for controlling the mixture ratio under various operating conditions 35 comprising means for controlling the opening movements of the secondary air valve on opening of the primary throttle and means operated by the primary throttle for regulating the effect of said controlling means. 40

14. A charge forming device for internal combustion engines comprising a plurality of primary mixture passages each of which is adapted to deliver a primary mixture of fuel and air to one of a plurality of secondary mixing chambers, 45 means for supplying fuel and air to each of said primary mixture passages, a single primary throttle valve for controlling the flow of mixture through all of said primary mixture passages, a single secondary air passage adapted to supply 50 air to all of said secondary air passages, a secondary air valve in said secondary air passage, means for controlling the proportions of fuel and air in the mixture formed in all of the secondary mixing chambers comprising means for control- 55

- ling the opening movement of the secondary air valve and means operated by the primary throttle for variably regulating the effect of said controlling means.
5. 15. A charge forming device for internal combustion engines comprising a mixture passage, means for supplying fuel and air thereto, a throttle controlling the flow of mixture through said passage, a secondary air valve for supplying additional air to said mixture passage, means to enrich the mixture upon opening movements of the throttle comprising a fuel pump and means for retarding the opening of the secondary air valve, and means operable when the throttle approaches full open position to reduce the retarding effect of said retarding means to decrease the degree of mixture enrichment under such operating conditions.
10. 16. A charge forming device for internal combustion engines comprising a mixture passage, means for supplying fuel and air thereto, a throttle controlling the flow of mixture through said passage, a secondary air valve for supplying additional air to said mixture passage, means to enrich the mixture to a relatively great degree upon opening movements of the throttle at relatively low speeds, said last named means comprising a fuel pump and means for retarding the opening of the secondary air valve, and means operable by the throttle upon opening movements thereof at higher speeds to reduce the effect of said retarding means so as to reduce the enriching effect at high speeds.
15. 17. A charge forming device for internal combustion engines comprising, in combination, a mixture passage, fuel and air inlets therefor, a throttle for regulating the flow of mixture through said passage, a main air valve controlling the admission of air, a secondary air valve for regulating the fuel mixture ratio, means for retarding the opening movement of said secondary air valve to enrich the mixture, and means operable when the secondary air valve approaches its open position to reduce the retarding effect of said retarding means on said air valve.
20. 18. A charge forming device for internal combustion engines comprising, in combination, a mixture passage, fuel and air inlets therefor, a throttle for regulating the flow of mixture through said passage, a main air valve controlling the admission of air, a secondary air valve for regulating the fuel mixture ratio, means for retarding the opening movement of said secondary air valve to enrich the mixture, a dash pot opposing opening movement of said auxiliary air valve, and means operable when the secondary air valve approaches open position to reduce the resistance offered by said dash pot to the opening of said air valve.
25. 19. A charge forming device for internal combustion engines comprising, in combination, a mixture passage, fuel and air inlets therefor, a throttle for regulating the flow of mixture through said passage, a main air valve controlling the admission of air, a secondary air valve for regulating the fuel mixture ratio, means for retarding the opening movement of said secondary air valve to enrich the mixture, a dash pot opposing opening movement of said secondary air valve, adapted when open to reduce the resistance of the dash pot to opposing movement of the secondary air valve, and means operable when the secondary air valve approaches open position to open the dash pot valve.
30. 20. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, means for retarding the opening of the valve under certain conditions to enrich the mixture, a fuel pump operable to supply additional fuel to also enrich the mixture, and means operable by the fuel pump to control the retarding effect of said retarding means on the said air valve.
35. 21. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, means for retarding the opening of the valve under certain conditions to enrich the mixture, a fuel pump operable to supply additional fuel to also enrich the mixture, and means operable by the fuel pump to reduce the effect of the said retarding means on the air valve as the latter approaches its open position.
40. 22. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, means for retarding the opening of the valve under certain conditions to enrich the mixture, a fuel pump operable concurrently with the air valve to supply additional fuel to the mixture passage for also enriching the mixture and means operable by the fuel pump as the end of a pumping operation is approached to reduce the retarding effect of said retarding means on said air valve.
45. 23. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, a dash pot for retarding the opening of the air valve, a valve for controlling the effectiveness of the dash pot, a fuel pump for supplying additional fuel to also enrich said mixture, and means carried by said fuel pump for operating said valve.
50. 24. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, a dash pot for retarding the opening of the air valve, a valve for controlling the effectiveness of the dash pot, a fuel pump for supplying additional fuel to also enrich said mixture, an operating rod for said fuel pump, and a lug carried by said rod and adapted to engage said last named valve to operate the latter and vary the effectiveness of the dash pot.
55. 25. A charge forming device for internal combustion engines comprising, in combination, a mixture passage, means for supplying fuel and air thereto, a throttle controlling the flow of mixture therethrough, an air valve for regulating the admission of air and for controlling the fuel-air ratio of the mixture supplied to the engine, a dash

pot for retarding the opening of the air valve, a valve for controlling the effectiveness of said dash pot and adapted when open to reduce such effectiveness, a fuel pump for supplying additional fuel to also enrich the mixture and means whereby the fuel pump operates said valve.

26. A charge forming device for internal combustion engines comprising in combination, a plurality of primary mixture passages for supplying a primary mixture of air and fuel to the engine intake ports, an air passage for conveying air only to said intake ports, a main air valve

regulating the admission of air to both the primary mixture passages and air passage, an auxiliary air valve controlling the passage of air through said air passage only and operable to control the ratio of the fuel mixture supplied to the engine, means for retarding the opening movement of the auxiliary air valve to enrich the mixture and means operable when said auxiliary air valve approaches its open position to reduce the retarding effect of said retarding means. 10
